UNITED STATES PATENT OFFICE.

OSCAR J. ZIEGLER, OF FREEPORT, ILLINOIS.

FEED CRUSHER AND GRINDER.

SPECIFICATION forming part of Letters Patent No. 625,081, dated May 16, 1899.

Application filed September 17, 1897. Serial No. 651,967. (No model.)

To all whom it may concern:

Be it known that I, OSCAR J. ZIEGLER, a citizen of the United States of America, residing at Freeport, in the county of Stephenson 5 and State of Illinois, have invented certain new and useful Improvements in Feed Crushers and Grinders, of which the following is a specification.

The object of this invention is to provide a feed-grinder that when connected with an ordinary windmill will operate without attention and without clogging and grind at a rate proportional to the force of the wind even though the wind should at times allow the apparatus to come to rest. Ordinarily when feed-grinders gradually come to rest through lack of wind there is congestion in the burs or crusher, if a crusher is employed, or in both, and once stopped in this way the mill will not again start until the wind exerts a force many times that needed for grinding at an ordinary rate, for there is no movement, unless breakage occurs, until the force is sufficient to overcome in an instant both the resistance of the 15 congested material and the inertia of the whole moving portion of the apparatus, including the windmill itself. To accomplish the desired result, I place above ordinary grinding-burs a breaker of such character 20 that it cannot offer serious resistance, even if its discharge be wholly prevented, and impart to this breaker a slow movement transmitted through power-multiplying gearing. Between the breaker and the burs are interposed devices that normally take from the breaker and deliver to the burs the material to be ground by the latter and at a rate governed by the speed of the burs, the arrangement, however, being such that while the 25 burs are moving too slowly for effective work, and yet are by no means at rest, delivery practically ceases. If, then, the wind dies away, the mill stops with little or no material between the burs; but when it again increases 30 or rises the mill starts, and as soon as the movement is rapid enough for any effective work the feed or delivery to the burs gradually begins again and keeps pace with the speed of the burs. Means are also provided 35 whereby the rate of feed for any given speed of the burs may be varied in accordance with the character of the material to be ground or

the fineness of grinding desired, it being, of course, understood that if the material offer great resistance or if the burs be set for very fine grinding the delivery should be slower. 55

In the drawings, Figures 1 and 2 are respectively side and end elevations of the machine. Fig. 3 is a plan view, a certain hopper being omitted. Fig. 4 is a similar view with certain 60 breaking mechanism also omitted. Fig. 5 is a section on the line 5 5, Fig. 1. Fig. 6 is a section on the line 6 6, Fig. 3. Fig. 7 is a section on the line 7 7 of Fig. 1. Fig. 8 is an elevation looking from the right in Fig. 1. Fig. 9 is a section on the line 9 9 of Fig. 8. Fig. 10 is a section on the line 10 10 of Fig. 9.

In the views, A A' A² A³ represent a rigid frame supporting all other parts of the machine. In this frame is mounted a power-shaft S, driven by a windmill-shaft S' through gears V V'. The shaft S, acting through a gear D' and pinion P³, drives a shaft d, having at one end a bur K' and at the other a fly-wheel W. This bur and a companion non- 75 rotary bur K are inclosed in a chamber C', fed from a hopper C and having an outlet C². At some distance above the parts just mentioned is a breaker consisting of two parallel separated shafts R, provided with widely- 80 spaced breaking-teeth. The shafts are connected by gears P P', and their toothed portions lie within a chamber B, having above a hopper B' and below a discharging-neck B². One of the shafts bears a gear D, which receives power from the shaft d through gears P² P'. Below the discharge-opening of the 85 chamber B is an inclined feeding-spout H, having its lower open end above the hopper C and adjustably supported from a hook j on the chamber B by means of a strap I, provided with perforations i and engaging both the hook and a bail h', attached to the spout. The other end of the spout is pivotally supported from the chamber B by a link g, provided at its projecting lower end with a fork or yoke G to embrace an eccentric f' upon a small shaft f. The latter shaft is rotated from the shaft d by means of sprocket-wheels d' F and a chain E, and as it rotates the rear 90 end of the spout is obviously swung from side to side at a speed corresponding to the speed of the shaft d. If now the inclination of the spout be properly adjusted with reference to 95 100

the fineness of the desired grinding and the character of the material to be ground, the mill will thereafter take care of itself, for when the speed of the burs falls below a certain rate the shaking of the spout is so slight that practically no delivery therefrom is induced and the material in the burs is ground and discharged. Meantime the breaker-teeth first break such material as falls in their paths and thereafter move through the broken mass without causing any material congestion. Should the wind-wheel stop, the burs and breaker come to rest, of course; but so soon as the wind-wheel exerts force enough to be of practical value in grinding that force is amply sufficient to overcome any slight resistance of the material in the breaker and again set the burs and breaker in motion, and so soon as that motion is sufficient for grinding the delivery to the burs begins and in rate follows the speed of the burs.

What I claim is—

1. The combination with grinding mechanism, of a breaker mounted above said mechanism and adapted to operate whether or not it is permitted to discharge its product, and automatic devices arranged between the breaker and grinding mechanism to interrupt the discharge from the breaker when the speed of the grinding mechanism falls below a predetermined rate.
2. The combination with grinding mechanism and adapted to operate whether or not it is permitted to discharge its product, devices receiving material from the breaker and delivering it to the grinding mechanism, means whereby the speed of the grinding mechanism governs the rate of such delivery, and means for at will adjusting the rate of such variable delivery.

3. The combination with the frame supporting the bur-chamber below and the breaker-chamber above, of the bur-shaft, the burs within the first chamber, the toothed breaker-shafts in the second chamber, the vibrating, adjustably-inclined spout mounted in position to receive material from the breaker-chamber and deliver it to the bur-chamber, the power-shaft geared to the bur-shaft to drive it at high speed, the gearing operated by the bur-shaft to drive the breaker-shafts at a low speed, a shaft bearing an eccentric arranged to oscillate said spout, and sprocket-and-chain mechanism driving the eccentric-shaft from the bur-shaft.

In witness whereof I have hereunto set my hand, at Freeport, in the county of Stephenson and State of Illinois, this 30th day of August, A. D. 1897.

OSCAR J. ZIEGLER.
